TOMASO SALVATORE COGLIOLO, OF GENOA, ITALY, ASSIGNOR TO SOCIETÀ ESERCIZIO BACINI, INDUSTRIALS, OF GENOA, ITALY.

MARINE PROPELLER.

1,352,877.

Specification of Letters Patent. Patented Sept. 14, 1920.

Application filed February 13, 1917. Serial No. 148,467.

To all whom it may concern:

Be it known that I, TOMASO SALVATORE COGLIOLO, a subject of the King of Italy, residing at Genoa, Italy, have invented certain new and useful Improvements in Marine Propellers, of which the following is a full, clear, and exact specification.

This invention relates to improvements in propellers, particularly marine propellers, and an object of the invention is to provide a propeller blade with a surface adapted to move in axial direction with the least possible slippage, so as to increase the efficiency of the blade.

15 It is known to make propeller blades having a straight generatrix, and these propeller blades have been found to be fairly efficient. It is also known to make blade surfaces having a parabolic generatrix; and 20 while in the use of blades having a parabolic generatrix certain phenomena occur which do not occur in the use of a straight generatrix blade, the efficiency of the blades having a straight generatrix, as well as the efficiency 25 of the blades having a parabolic generatrix, can be increased by a combination of the two surface shapes.

It is an object of the present invention to develop from a straight generatrix blade a 30 blade having a parabolic generatrix, by transposing parallel to the axis of the propeller the sine curves which constitute the lateral projections of the spiral sections which serve for building up the blade itself. 35 This transposition of the various sine curves is proportional to the distance of corresponding points of the parabolic generatrix from those of the straight generatrix.

Owing to the transposition described, the 40 projection of the propelling surface of the blade into a vertical plane containing the axis of the propeller is reduced to a minimum without alteration of the pitch of the propeller taken as the basis of construction. 45 Due to this reduction of this projected area, the action of the propeller will produce a slight component in transversal direction only, and the entire, or approximately entire, power applied to the propeller shaft 50 will be consumed in the longitudinal advancement movement of the propeller in direction of its axis.

The formation of the improved propeller surface from an ordinary straight genera-

trix propeller is illustrated in the accompanying drawing, wherein—

Figure 1 is a front elevation, diagrammatically shown, of a straight generatrix propeller blade;

Fig. 2 is a side elevation, also diagrammatically shown, of the same straight generatrix propeller blade;

Fig. 3, corresponding to Fig. 1, shows diagrammatically a front elevation of the same propeller blade, to illustrate the fact 65 that the transformed propeller blade has the same diameter and pitch as the original propeller blade;

Fig. 4 shows diagrammatically the actually transformed propeller blade having 70 a parabolic generatrix, and

Fig. 5 is a side view of the propeller on a reduced scale.

The shape of the edges of the propeller blade, as indicated at S_u and S_e , may be 75 found in the ordinary way as a harmonic curve composed of portions of a spiral the equation of which is known. The radius of the propeller blade extending from the center of the hub to the point 7, located on a 80 line G , which may serve as generatrix of the blade, is also given by the requirements of the particular case. In order to construct from this front elevation of the propeller blade the side elevation of the same as illustrated in Fig. 2, a plurality of circular sections are assumed in the front elevation, and the points of intersection of these circular sectional lines with the front and rear edges S_u and S_e and with the generatrix G 90 are determined and are indicated at $0u$ to $6u$, $0e$ to $6e$, and 0 to 7 respectively.

The sectional lines 1, $1u$, $1e$ or 2, $2u$, $2e$, etc., appearing as circular arcs in front elevation must appear as sine curves in side 95 projection of the propeller blade. All of these sine curves corresponding to the common center of the circular sectional lines have a common point of intersection with the axis of the propeller, this common point 100 of intersection with this axis being indicated at A in Fig. 2. The sine curves, furthermore, all have the same periodicity, the apices of the curves being located in the generatrix G , which is a side elevation of 105 the straight line generatrix G shown in Fig. 1. The distance of the common point of intersection A of the sine curves with the

axis of the propeller from the generatrix G is assumed by experience to be advantageously one-fourth of the pitch of the propeller, and is indicated as such in Fig. 2 of 5 the drawings.

The points 0 to 7 of Fig. 1 then being projected horizontally to the generatrix G thus located with respect to the point of intersection A, define the apices of the sine 10 curves, which then can be drawn through these projections 0 to 7 in Fig. 2 and through the common point of intersection A.

To define, then, the shape of the edges S_u and S_e of the propeller blade in side elevation, it is merely necessary to project 15 horizontally the points of intersection of the curves S_u and S_e with the circular arcs of Fig. 1 to the corresponding sine curves 0 a , 1 a , 2 a , etc., and to connect these projected points as shown in Fig. 2, so as to 20 define the edges S_u and S_e .

The construction of propeller blades having a straight generatrix as just described is well known in the art, and is repeated 25 here merely for the purpose of facilitating the description of the development of the blade surface having a parabolic generatrix from the blade surface having a straight generatrix having the same pitch and the 30 same radius, but having a considerably reduced area of longitudinal projection.

For this purpose the front elevation of the blade is constructed as shown in Fig. 1, Fig. 3 being identical therewith. The deformation of the straight generatrix blade into a parabolic generatrix blade with reduced projection is then accomplished by first drawing the parabolic generatrix indicated at G_d in Fig. 4. This may be a 40 parabola intersecting the straight generatrix at the end point 7 and having a perimeter which is in a certain predetermined relation to the radius of the blade. In the example illustrated, the perimeter of the 45 parabola is given as about one-third of the radius, or .328 R . The sine curves drawn in Fig. 2 through the straight generatrix, in which the apices are located at 0, 1, 2, etc., are then transposed to have their apices in 50 the parabolic generatrix G_d of Fig. 4, and it is obvious then that they do not have a common point of intersection with the axis of the propeller. The location of the apices 0, 1, 2, 3, 4 on the parabolic generatrix G_d 55 is found by horizontally projecting the points 0, 1, 2, etc., from the straight generatrix G of Fig. 3.

The periodicity of the various sine curves found in Fig. 2 being uniform, it is obvious 60 that the periodicity of the sine curves transferred to Fig. 4 also is uniform, and that the points of intersection of these sine curves of Fig. 4 with the longitudinal axis of the propeller will have the same relation to 65 each other as the projections of the apex

points in the generatrix G_d upon the axis of the propeller will have to each other. The axial distances of these apices are expressed in fractions of the radius R , and if, therefore, from the point of intersection of the 70 generatrix G_d with the axis, as indicated at E' , a distance equal to one-fourth of the pitch is measured along the axis to the point E , the intersecting points of the various sine curves with the axis will be found 75 by measuring the distances from E to the intersecting points with the axis equal to the projections $E'0$, $E'1$, as shown in Fig. 4. The location of the apex and intersection of the curve with the axis being given, 80 the sine curves may then be drawn in Fig. 4, and on these sine curves the points $6u$, $5u$, etc., and $6e$, $5e$, etc., may be found by projecting the corresponding points from the front elevation until the entire edge S_u and 85 S_e in the side elevation is found.

The propeller blade constructed in this way, having the same front elevation as a straight generatrix blade, the same radius, and the same pitch, has a considerable area 90 of longitudinal projection resulting in a reduction of those features which have a tendency to decrease the efficiency of the propeller blade.

I claim:

1. A propeller, having a blade the surface of which has a parabolic generatrix, but wherein the several points of the blade surface are transposed parallel to the axis of the propeller distances equal to the distances of corresponding points of projection from a straight generatrix to said parabolic generatrix.

2. A propeller, having a blade the surface of which has a parabolic generatrix, 105 but wherein the several points of the blade surface are transposed parallel to the axis of the propeller predetermined distances, said distances being proportional to the distances of predetermined points on a straight 110 generatrix from corresponding points of a parabolic generatrix, which intersects the straight generatrix at the terminal points of the latter.

3. A propeller having a blade the surface of which has a parabolic generatrix transformed from a straight generatrix blade by transposing the sine curves which constitute the projections of the spiralic sectional lines of the straight generatrix 120 blade (and which intersect the propeller axis in a common point) until the apices of said sine curves are located in the parabolic generatrix.

In testimony whereof I affix my signature 125 in presence of two witnesses.
